UNITED STATES PATENT OFFICE.

WALLACE C. MILLS, OF ROCKFORD, ILLINOIS, ASSIGNOR TO J. L. CLARK MANUFACTURING CO., OF ROCKFORD, ILLINOIS, A CORPORATION OF ILLINOIS.

SPOOL OR REEL.

Application filed May 28, 1928. Serial No. 281,011.

The invention pertains to spools of the type comprising a tubular core with substantially flat sheet metal heads secured upon opposite ends of the core. Such spools are adapted to 5 contain thread, wire, adhesive tape, etc., and are made in varying sizes depending upon the purpose for which they are to be used. The heads are customarily lithographed to present an attractive appearance and to identify 10 the manufacturer of the contents of the spool, or the seller thereof, and to impart any other desired information.

With the foregoing in view, the object of the invention is to provide a spool of the character indicated having heads fastened onto the ends of the tubular core in a manner such as to provide for strength and rigidity; smooth uninterrupted surfaces at the ends of the core; economy of manufacture with a 20 minimum stressing of the metal; and neatness in appearance.

Another object is to provide a rigid fastening for the heads of the spool without the formation of undesirable grooves or crevices 25 between the head and the core.

Strength and rigidity in the fastening of the heads on the ends of the core is especially desirable where the spool is to be used for winding fine wire, silk thread, or other material having a tendency to pack and spread the heads of the spool apart, so as to become wedged between the heads and the body of the material being wound. Similarly, the absence of outwardly opening grooves, 30 cracks or crevices in the joint between the core and the inner surface of the heads is also desirable in the case of wire, thread and the like, to prevent the same from becoming caught so as to interfere with the unwinding 35 operation.

Smooth uninterrupted surfaces at the ends of the core are especially advantageous where the spool is to be used for adhesive tape, since it is customary for the user to insert a thumb or finger into the end of the core while the spool is being revolved in the operation of unwinding tape, and any sharp raw edges will injure the fingers or cut and tear rubber gloves such as are used by 40 surgeons. Economy of manufacture is desirable for obvious reasons, but it is especially advantageous when coupled with rigidity of construction and with freedom from an undue stressing of the metal of the head. In 45 the latter respect, where substantial stressing

of the metal is necessary, undesirable wrinkles are apt to be produced which distort the lithographed surface of the head and detract from the appearance thereof.

The foregoing objects, together with other 60 and ancillary advantages, are attained by the use of a connecting member formed from a flat sheet of metal to provide a complete annulus fitted into the end of the core and interlocking with the end of the core and the 65 inner edge of the flat ring forming the head.

In the drawings:

Figure 1 is a side elevation of a spool of the type referred to.

Fig. 2 is a central vertical sectional view of 70 one end of the spool on a slightly larger scale.

Fig. 3 is a fragmentary central sectional view through one end of the spool and showing the parts assembled, but before the interlocking operation.

Fig. 4 is a similar view but showing the parts after the interlocking operation.

Fig. 5 is a detail view showing a modified form.

Fig. 6 is a central vertical sectional view 80 on a large scale through one end of a spool especially adapted for adhesive tape.

In the drawings 7 designates the tubular body or core of the spool and 8 the heads fastened on opposite ends of the core. The core 85 is preferably formed from a flat sheet of metal rolled into tubular form, the opposite ends of the sheet meeting at 9. In some instances these meeting edges are united by a suitable seam but are herein shown without 90 such a seam in slightly spaced relation.

The head 8 is formed from a sheet of metal centrally apertured so as to form a flat ring, the outer peripheral edge of which may be curled as at 10 for finishing and strengthening purposes. The heads are customarily lithographed for purposes of identifying the manufacturer or to convey any other desired information, this being done before the heads are assembled onto the ends of the core.

The heads 8 have an internal diameter such as to fit rather snugly over the ends of the core and in the construction employed in Figs. 2 and 4, each head is formed with a flange 11 defining the central aperture in the head. Also as shown in said figures, the head is seated upon an annular shoulder which in the present instance is formed by an outwardly projecting bead 12 spaced a short distance from the end of the core (Fig. 3). 110

The flange 11 thus encircles the end portion of the core extending beyond the bead 12, and extends in a direction toward the end of the core.

5 The head and core are rigidly interlocked with each other and with a connecting member generally designated by the numeral 13. This member is made from a flat sheet of metal shaped to provide an annulus 14 U-shaped in form and adapted to receive within it the end of the core and the encircling flange 11. The outer peripheral leg of the U-shaped annulus terminates short of the outer face of the head and the inner leg of the annulus is 15 of a length such that when the parts are interlocked (Fig. 4) it extends into the core substantially beyond the bead 12.

In interlocking the end of the core with the head and with the connecting member 13, 20 the annulus together with the end of the core and the flange 11 are pressed together and bent outwardly into a position substantially at right angles to the axis of the core. At the same time axial pressure flattens the bead 25 and the result is that the annulus serves to bind the end of the core and the flange 11 together with the head clamped between the bent or flanged end of the core and the annular shoulder formed by the bead. It will be 30 noted that the outer leg of the annulus 14 is turned inwardly so as to engage in the outwardly opening groove formed between the flange 11 and the head, while the inner leg of the annulus is curled around the end of the 35 core and into the end thereof. Finally, the head is offset as at 15 to receive the flattened bead, the inner face of the latter being substantially flush with the inner face of the head. This latter feature is especially ad- 40 vantageous where the spool is to be used in winding wire or thread for the reason that the offset portion 15 serves to cover the outwardly opening crevice which would otherwise be formed between the bead and the 45 head.

Preferably the connecting member 13, in the case of the larger spools, includes an end wall 16 formed integral with the inner leg of the annulus 14 and constituting an inward extension of the head 8. The opposite end walls 16 may be centrally apertured as at 17 to receive the ends of a small tube 18, each end of the tube being bent outwardly into engagement with an oppositely turned edge 19 55 of the opening in the end wall 16. Such a tube is made of a diameter corresponding to mandrels of standard size used in rotating the spools when winding wire or the like. Moreover it serves as a stay between the opposite ends of the spool, lending greater strength thereto.

In the form shown in Fig. 5, the central tube is omitted, the opening 17 having an in-turned edge 20. These openings permit the 60 spool to be placed upon a rod or shaft to fa-

cilitate the dispensing of the material on the spool. Also the bead on the end of the core is omitted in this form, the interlocking of the annulus with the end of the core and with the flange 11 on the head serving to hold the 70 parts against endwise relative movement. On the other hand the flange 11 is omitted from the construction shown in Fig. 6, the head being held against movement in a direction away from the end of the core by the 75 bead 12.

In Fig. 6 the end wall 16 is omitted, the inner leg of the annulus being turned outwardly into engagement with the wall of the core below the bead, as at 21. This construction 80 is employed in the case of smaller spools used for adhesive tape, where the spool is held in the hand of the user while removing tape. Here the connecting member serves as a guard ring covering the raw edges of the 85 metal at the slot 9 in the core.

It will be observed that by the construction provided the heads of the spool are not only securely connected to the ends of the core but the connection is reinforced by the interlocking annulus so as to resist spreading of the heads. Also the annulus provides a smooth uninterrupted surface at the end of the core for the protection of the user in the case of adhesive tape spools. At the same 90 time, the interlocking of the parts is effected without any danger of stressing, breaking or otherwise injuring or weakening the metal of the head and of the connecting member. This is especially important from the stand- 95 point of economy in manufacture in that it enables the use of ordinary commercial stock sheet metal and simplifies the assembling and forming operation, due to the fact that it reduces the number of forming operations, 100 and it is unnecessary to use a lubricant on the dies which must subsequently be wiped off of the spools.

This application is a continuation in part of my prior application Serial No. 141,317, 110 filed Oct. 13, 1926.

I claim as my invention:

1. A metallic spool comprising, in combination, a tubular body bent from a flat sheet of metal and having an annular bead near 115 but spaced a short distance from one end, a head having a central aperture with an out-turned flange defining the aperture and adapted to receive the end of said tubular body, and an endless annular ring of U-shaped cross-section fitted over the free ends of said body and said flange, said end portion of the body being bent to form with said bead an outwardly opening groove in which said head is clamped, and said ring providing a curl passing around the body and into engagement with the head to secure said head against said bead.

2. A metallic spool having, in combination, an elongated tubular body shaped to form

an outwardly opening annular groove at one end, a head having a flanged edge projecting into said groove, and an annular member engaging said flanged edge of the head and curled around the end of said tubular body.

5 3. A metallic spool comprising, in combination, a tubular sheet metal body having a bead near one end and an extension beyond said bead, a disk having a central aperture receiving said extension, said aperture being defined by an outwardly turned flange, a member of U-shaped cross-section receiving said flange and said extension, said member, said extension, and said flange being bent outwardly against the outer face of said head to form an interlocking joint.

10 4. A metallic spool comprising, in combination, a tubular body bent from a sheet, the terminal ends of which form a narrow slot, a disk-shaped head receiving one end of said body, and a separately formed endless member interlocking with said head and the end of said body to secure them together, said member having a portion fitting into the end 25 of the body so as to cover the end of said slot.

15 5. A spool comprising, in combination, a tubular body bent from a sheet the terminal ends of which form a slot in the body, said body having an annular bead near one end and a flanged end spaced from said bead, a disk having a central aperture receiving the end of the body and positioned between said bead and said flanged end of the body, and 30 an annular member having one edge portion disposed between said disk and said flanged end of the body and then bent reversely to extend around the end of the body and into said body to cover the end of said slot.

35 6. A spool comprising, in combination, a tubular sheet metal body having an outwardly extending bead near one end and an extension beyond said bead, a disk having a central aperture receiving said extension, a separately formed annular member of U-shaped cross-section receiving said extension, said extension and said member being bent outwardly against the outer face of said disk.

40 7. A spool comprising a tubular core, a head, and an annulus interlocked with the core and the head, said core being formed from a tubular member having a shoulder against which the head is adapted to seat, and said annulus being formed from a piece of sheet metal bent into U-form to receive the end of the core, said annulus and said core being bent outwardly to clamp the head upon said shoulder.

45 8. A spool comprising a tubular core, a head on one end of the core, and a connecting annulus for the head and the core, said head having a flange encircling one end of the core and said connecting annulus being formed from a sheet of metal bent into U-form to receive the end of the core and said

flange, and said annulus together with the end of the core and said flange being bent outwardly to a position substantially perpendicular to the axis of the core whereby to interlock the head and the core together.

70 9. A spool comprising a tubular core, heads on opposite ends of the core, and connecting members for securing the heads on the core, each of said connecting members comprising an annulus formed from a flat sheet of metal 75 and serving to bind said core and head together in interlocking relation, and an end wall formed integral with the annulus spaced from the end of the core, each of the end walls being apertured, and a tubular member having its opposite ends passing through the apertured end walls and interengaging therewith.

10 10. A metallic spool comprising, in combination, a tubular sheet metal body having an outwardly extending bead near one end, a disk having a central aperture and adapted to seat upon said bead, an annular member interlocked with said body and serving to clamp said disk upon said bead, said disk 90 being offset adjacent the body whereby to receive the bead with the inner face of the latter substantially flush with the inner face of the disk.

95 11. A metallic spool comprising, in combination, a tubular sheet metal body having an outwardly extending bead near one end and an extension beyond said bead, a head seated upon said bead and interlocked with said extension on the body, said head being 100 in the form of a flat metal disk offset adjacent the body to receive said bead with the inner face of the bead substantially flush with the inner face of the disk.

105 12. A spool comprising a tubular core formed of sheet metal, a head in the form of a disk centrally apertured to receive the end of the core, said core being formed to provide a shoulder against which the head is adapted to seat, a flange on the head defining the aperture therein and encircling the end of the core, and an annulus formed from a flat sheet of metal bent into U-form to receive the end of the core and said flange, said annulus together with the end of the core and 115 said flange being bent outwardly to a position substantially perpendicular to the axis of the core whereby to interlock the head and the core together with the head against said shoulder.

120 13. A spool comprising, in combination, a tubular sheet metal body having an outwardly extending bead near each end and extensions beyond said bead, a pair of heads formed of sheet metal and seated upon said beads, a pair of connecting members formed of sheet metal and serving to bind the heads on the body, an end wall for the body formed integral with the annulus, and a tubular member connecting said end walls.

14. A spool comprising a tubular core, a head for each end of the core comprising a disk formed from a flat sheet of metal with a central aperture therein and a flange defining said aperture, the end of the core and said flange being secured together, an annulus formed of sheet metal and having a part covering the joint between the disk and the core and a part extending into the end of the core, and a transverse centrally apertured end wall for the core, said end wall being formed integral with the part of the annulus which extends into the core.

15. A spool comprising a tubular core, a

head secured on each end of the core and comprising a disk formed from a flat sheet of metal with a central aperture therein adapted to receive the end of the core, and an annulus formed of sheet metal and fitting into the end of the core, said annulus extending from the outer face of the disk adjacent the core to a point within the core so as to cover the joint formed between the disk and the core, and a centrally apertured end wall for the core carried by the annulus.

In testimony whereof, I have hereunto affixed my signature.

WALLACE C. MILLS.
